CLAIM

The ornamental design for an inflatable jacket, as shown and described.

DESCRIPTION

FIG. 1 is a front perspective view of the inflatable jacket showing my new design;

FIG. 2 is a front elevational view thereof;

FIG. 3 is a rear elevational view thereof;

FIG. 4 is a right side elevational view thereof, the left side view being a mirror image of the right side view;

FIG. 5 is a top plan view of the inflatable jacket; and,

FIG. 6 is a bottom plan view thereof.
